UNITED STATES PATENT OFFICE.

ALFRED P. SEIDELL, OF BLOOMFIELD, NEW JERSEY, ASSIGNOR TO ORANGE LIGHTING FIXTURE MANUFACTURING CO., A CORPORATION OF NEW JERSEY.

DESIGN FOR A LIGHTING-FIXTURE PLATE OR ARTICLE OF ANALOGOUS NATURE.

Application filed June 8, 1928. Serial No. 27,056. Term of patent 7 years.

To all whom it may concern:

Be it known that I, ALFRED P. SEIDELL, a citizen of the United States, and a resident of Bloomfield, county of Essex, and State of New Jersey, have invented a new, original, and ornamental Design for a Lighting-Fixture Plate or Article of Analogous Nature, of which the following is a specification, reference being had to the drawing forming a part hereof.

In the drawing:

Figure 1 is an inverted plan view of the lighting fixture plate or article of analogous

nature, the part shown, in full line outline being ornamented in the same manner as the part more fully illustrated; and

Figure 2 is a side view, the part shown in full line outline being ornamented in the same manner as the part more fully illustrated.

I claim:

The ornamental design for a lighting fixture plate or article of analogous nature substantially as shown and described.

ALFRED P. SEIDELL.
